PINLESS CLOTHESLINE

Filed Aug. 29, 1929

UNITED STATES PATENT OFFICE

LLOYD F. MARTIN, OF MOREHEAD, KENTUCKY

PINLESS CLOTHESLINE

Application filed August 29, 1929. Serial No. 389,243.

This invention relates to clothes lines, and aims to provide a clothes line of the pinless type and embodying links so constructed that articles to be dried on the line, may be frictionally held within the loops of the links.

An important object of the invention is to provide a clothes line including line sections arranged in parallel spaced relation with each other, so that the maximum number of articles may be supported by the clothes line in the minimum amount of space.

A further object of the invention is to provide removable spacing members between parallel line sections so that the spacing members may be removed and replaced by longer or shorter spacing members, thereby adapting the clothes line for use in supporting articles of various weights and sizes.

A still further object of the invention is to provide loop members or hangers at the ends of the line, so constructed that they will prevent twisting or turning of the line while in use.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a perspective view illustrating a clothes line constructed in accordance with the invention.

Figure 2 is an enlarged perspective view illustrating one end of the clothes line.

Figure 3 is an enlarged perspective view of one end of a modified form of clothes line.

Referring to the drawing in detail, the clothes line embodies a pair of line sections 5 and 6 respectively, the line sections being arranged in parallel spaced relation with each other, as clearly shown by the drawing, and while I have shown two line sections as held in parallel spaced relation with each other, the number of parallel line sections may be varied to meet the requirements of use, with-

in the scope of the invention. Each line section embodies a plurality of links, each link comprising a length of wire material bent upon itself to provide a loop 7 at one end thereof, and a pair of leg members 8, one end of the length of wire material being formed into a loop 9, while the opposite end is bent around the loop 9, at 10, securing the ends together.

The leg members 8 are twisted around each other to form gripping surfaces where they contact, one of the leg members being offset as at 11 providing an eye or an enlarged opening to permit one corner or end of the article supported by the line, to be slid into position between the gripping surfaces of the legs 8.

In assembling the line, the loop 9 at one end of one link member is interlocked with the loop 7 of the adjacent link member to form a continuous line. On arranging the line sections in parallel spaced relation with each other, the offsets 11 of the links are arranged in staggered relation with respect to each other, so that the articles hanging on one line section will not interfere with the articles hanging on the adjacent line section.

The reference character 12 designates spacing members which are formed of lengths of wire having hooks 13 at their ends to be hooked over adjacent links, in a manner as shown by Figure 2, so that the line sections will be held in proper spaced relation at all times. Connected with the end links of the chain sections, are hanger loops 14 which are substantially U shaped, the free ends thereof being formed with openings through which the wire material of which the links are constructed, is passed. Thus it will be seen that when these hanger loops are positioned over hooks such as shown by Figure 1 of the drawing, the line sections will be held in their proper supporting positions and will be prevented from twisting.

When it is desired to space the line sections at such distances apart as to support heavy articles such as blankets or the like,

the spacing members 12 may be removed and replaced by longer spacing members.

In the modified form of the invention as illustrated by Figure 3, a spacing member 15 is shown and embodies a length of wire formed with openings in its ends to receive the links of the line sections to permanently secure the spacing members of this form of line, to the links.

I claim:

- 10 1. A pinless clothes line embodying line sections arranged in parallel spaced relation with each other, each section embodying links, each link comprising a length of wire material bent upon itself to provide end loops and leg members twisted together providing gripping surfaces to grip articles therebetween, and removable spacing members between the line sections.
- 15 2. A pinless clothes line embodying line sections arranged in parallel spaced relation with each other, each section embodying links, each link comprising a length of wire material bent upon itself to provide end loops, the end loops of one link being interlocked with the end loops of the adjacent links, each of said links having leg members twisted around each other to provide gripping surfaces, one of the leg members of each link having an offset portion defining an eye to permit the articles to be moved between the gripping surfaces, and the offset portions of the line sections being arranged in staggered relation with each other.
- 20 3. In testimony that I claim the foregoing as my own, I have hereto affixed my signature.

LLOYD F. MARTIN.
